INVENTOR:

George W. Amos

Robert Burns
Attorney.

UNITED STATES PATENT OFFICE.

GEORGE W. AMOS, OF CHICAGO, ILLINOIS, ASSIGNOR OF ONE-HALF TO
SIDNEY S. NILES, OF SAME PLACE.

AXLE-NUT ATTACHMENT.

SPECIFICATION forming part of Letters Patent No. 362,922, dated May 17, 1887.

Application filed September 23, 1886. Serial No. 214,373. (Model.)

To all whom it may concern:

Be it known that I, GEORGE W. AMOS, a citizen of the United States, and a resident of Chicago, in the county of Cook and State of Illinois, have invented certain new and useful Improvements in Axle-Nut Attachments; and I do hereby declare the following to be a full, clear, and exact description of the same, reference being had to the accompanying drawings, in which—

Figure 1 is an axial section of the front portion of a vehicle-hub to which my improvements are adapted; Fig. 2, a transverse section of the same at line $x-x$; Fig. 3, a similar view at line $y-y$; Fig. 4, a detail elevation of the parts in an engaged position, the hub and band being shown in section; Fig. 5, a similar view of the parts in a disengaged position; Fig. 6, a face view of the axle-nut; and Fig. 7 an elevation, partly in section, of a modified arrangement of parts.

Similar letters of reference indicate like parts in the several views.

My invention relates to that class of axle-nut attachments in which a wrench-head is arranged to move in the hub-band and engage the axle-nut, so that a rotation of the wheel will cause the axle-nut to screw upon the threaded axle end, or off from the same, as desired; and my present improvement has for its objects, first, to provide an improved construction of axle-nut, whereby the screwing or jamming too tightly of the same upon the axle end is prevented in a very effective manner; second, to supply a simple, cheap, and durable means for automatically disengaging the wrench-head from the axle-nut after the same has been turned or screwed up to its proper position on the axle end; third, to furnish means for securely holding the said wrench-head in a position out of engagement with the axle-nut after the same has been applied, and, fourth, to afford a simple and effective means for locking the cover-cap of the hub-band from disengagement after it has been screwed into place.

To enable others skilled in the art to which my invention appertains to make and use the same, I will now proceed to more particularly describe the mechanism employed to attain the above-mentioned objects.

Referring to the drawings, A represents one end of the axle, threaded in the usual manner; B, a portion of the hub; C, the outer hub-band, and D the axle-nut, provided with the usual washer-cavity for the axle-washer a .

In the present improvement this axle-nut is provided with one or more projecting lugs, d , parallel with its axis, and which are engaged preferably by a wrench-head, as hereinafter described, in applying or removing said nut to or from the threaded axle end. The forward or applying faces, d' , of such lugs are made beveled or inclined, as shown, so that with the increased resistance met with as the axle-nut reaches its proper position on the threaded axle end said inclined faces will cause the wrench-head to move longitudinally out of engagement therewith. The rear or removing faces, d'' , of the lugs will be made straight, or without the above-described bevel, as a positive attachment between the nut and its operating wrench-head is desirable in the operation of unscrewing the axle-nut.

This improved form of nut is adapted for use in connection with any suitable form of wrench-head that will engage its longitudinally-projecting lugs; yet preference is given to the construction of parts shown in the drawings, as providing a self-contained automatically-operating mechanism for applying and removing the nut when required. In this E represents the wrench-head, adapted to move longitudinally in the hub-band and caused to turn therewith by means of guide-splines c on the inner periphery of the hub-band, that are embraced by lugs on the wrench-head, as shown. Any other equivalent means for connecting said wrench-head in a longitudinally-adjustable manner to the hub-band may be employed, instead of that above described, without departing from the spirit of my invention.

The wrench-head E is provided with longitudinally-projecting lugs e , counterparts of the axle-nut lugs d , and with similarly-formed faces e' , as shown.

The longitudinal movement of the wrench-head E will be sufficient to bring the lugs e entirely out of the path of the lugs d , and the wrench-head is held in either an "in" or "out" position by the following means:

F are radially-moving bars, arranged to slide in the fore part of the wrench-head and having an outward tendency imparted to them by springs f, as shown. These bars, which I term 5 "spring latch-bars," bear against the inner periphery of the hub-band, and in their path are arranged inwardly-projecting V-shaped lugs c' upon the said hub-band. The inclined faces of these lugs constitute stops for retaining 10 the wrench-head in the required position until overcome by a superior force. Such force is supplied in moving the wrench-head into engagement with the axle-nut, when it is desired to remove the same, by the pressure of 15 the finger or other suitable means inserted through a central opening in the cap or cover G of the hub-band. Said force is supplied when the wrench-head is to be forced out or disengaged by the inclined faces d' e' of the lugs 20 d and e after the axle-nut has reached its proper position on the axle end.

It is evident that the relative position of the parts above described can be modified and transposed without affecting the working of 25 my improvement. For instance, the yielding contact or engagement formed by the inclined faces of the nut-lugs and the wrench-head may be transposed to any other suitable point between the nut and the point of frictional resistance caused by the latch-bars F, preferably between the wrench-head and the hub-band, as in such case the guide-splines c can be employed to form one member of the aforesaid yielding contact provision by arranging 30 them in a spiral or inclined direction to the axis of the parts. Again, the minor details of construction may be similarly varied.

In Fig. 7 I show one of such modified arrangements, in which springs H take the place 40 of the lugs c', and fixed lugs F' the place of the spring latch-bars F, to effect a like result to that before described.

In another modified arrangement (not illustrated) the lugs c' are replaced by a central 45 stem projecting inwardly from a wrench-cap and having inclined projections on its sides similar to the lugs c', that are engaged by a pair of spring-bars substantially similar to the spring latch-bars F, other than that their 50 springs are arranged to force them inwardly against the inclined faces or sides of the aforesaid central stem.

The hub-cap G screws into the hub-band in the usual manner, and is held from turning 55 by pin projection or projections g upon its inner face being engaged by corresponding recesses, e', in the outer face of the adjustable wrench-head E, when the same is in its outer position, which is its normal position during 60 the use of the vehicle.

I is a rubber or other cushion inserted in the cap G to form an abutment for the wrench-head E, to prevent rattling of the parts in use.

With my improvement the nut is always 65 held within the cavity of the hub in proper position to receive the threaded axle end. The

leakage of the lubricant is entirely prevented, as well as the soiling of the hands of the operator, in removing or applying the wheel; but what is of greater moment is the prevention 70 of any liability to breakage due to the jamming or binding of the same, which, with my improvement, is automatically relieved before a point of danger is reached.

Having thus fully described my said invention, what I claim as new, and desire to secure by Letters Patent, is—

1. In an axle-nut attachment, substantially as set forth, an axle-nut provided with an applying lug or lugs having the inclined face d', 80 substantially as set forth.

2. In an axle-nut attachment, substantially as set forth, an axle-nut provided with an applying lug or lugs having the inclined face d' and straight face d'', substantially as set forth. 85

3. A means for connecting hubs to axles, the same consisting of an axle-nut provided with an inclined-faced lug or lugs and an adjustable wrench-head provided with counterpart lug or lugs, substantially as set forth. 90

4. A means for connecting hubs to axles, the same consisting of an axle-nut provided with an inclined-faced lug or lugs, a longitudinally-adjustable wrench-head provided with counterpart lug or lugs, and a spring latch device, substantially as herein described, for holding the wrench-head in or out of engagement, substantially as set forth. 95

5. The combination, substantially as set forth, of the axle-nut provided with lug or lugs d, having inclined faces d' and straight faces d'', the wrench-head E, having counterpart lug or lugs, the spring latch-bars F, and hub-band C, having inclined lugs c', substantially as set forth. 100

6. In an axle-nut attachment, substantially as herein described, the combination of the adjustable wrench-head E, having recess e', the hub-cap G, having pin projection g, and hub-band C, for the purpose set forth. 105

7. In an axle-nut attachment, substantially as herein described, the combination of the adjustable wrench-head E and hub-cap G, provided with a rubber cushion, I, for the purpose set forth. 110

8. In an axle-nut attachment, substantially as herein described, the hub-band C, provided with inclined lugs c', arranged as described, and for the purpose set forth.

9. A means for connecting hubs to axles, 115 the same comprising an axle-nut, an adjustable wrench-head for the same, a frictional resistance device, as F, in combination with inclined engaging-surfaces located at a point between the axle-nut and the hub-band parts, 120 substantially as set forth.

In testimony whereof witness my hand this 20th day of September, 1886.

GEORGE W. AMOS.

In presence of—

ROBERT BURNS,
S. S. NILES.
